UNITED STATES PATENT OFFICE.

JOHN O. CARREY, OF ST. LOUIS, MISSOURI, ASSIGNOR TO CARREY-MORSE ENGINEERING COMPANY, OF ST. LOUIS, MISSOURI, A CORPORATION OF MISSOURI.

COMPRESSOR FOR REFRIGERATION SYSTEMS.

Application filed July 20, 1925. Serial No. 44,783.

This invention relates generally to compressors and more particularly to compressors for refrigeration systems, the objects of the invention being to provide a compressor 5 which is highly efficient, is silent in operation, and is of substantial and compact construction.

Further objects of the invention are to provide a compressor having a plurality of 10 compressing units, the cycles of operation of which are arranged in a definite relation whereby the compressor actuating or driving mechanism is placed under a constant load, thereby preventing back-lash of said driving 15 mechanism.

Still further objects of the invention are to simplify the construction and operation of the compressors of the class described and provide simple and efficient means for separating the oil from the refrigerant and conveying said oil into the main casing.

Other objects of the invention are to provide improved means for sealing the main shaft to prevent leakage of oil from said 20 casing, and to provide means cooperating with said shaft for guiding the pistons in their travels.

With these and other objects in view, my invention consists in certain novel features 30 of construction and arrangement of parts, hereinafter more fully described and claimed, and illustrated in the accompanying drawings, in which—

Figure 1 is a vertical cross section taken 35 longitudinally through the compressor.

Figure 2 is a vertical cross section taken transversely through the compressor.

Figure 3 is a horizontal cross section taken on line 3—3 of Figure 2.

Figure 4 is a bottom plan view of the compressing head used in conjunction with the compressor.

Figure 5 is a vertical cross section through one of the cylinders and the pistons operating 45 therein and showing the piston at the completion of the compressing stroke.

Figure 6 is a similar view showing the piston at the completion of the intake stroke.

Figure 7 is a top plan view of the piston.

Figure 8 is a horizontal cross section taken 50 on line 8—8 of Figure 7.

Figure 9 is a detail view of the piston.

Figure 10 is a vertical cross section taken transversely through the shaft sealing means of the device. 55

Figure 11 is a transverse cross section taken adjacent to the central sealing member of the shaft sealing device.

Figure 12 is a vertical cross section taken adjacent to the mounting of the diaphragm 60 member of the sealing device.

Figure 13 is a perspective detail view of one of the washers of special metal used in conjunction with my seal.

Figure 14 is a perspective detail view of 65 one of the metallic seal members utilized in the construction of my machine.

Figure 15 is an enlarged detail view showing the arrangement of the various members of the seal. 70

Figure 16 is a detail view of the float valve used for controlling the passage between the high pressure chamber and the main casing.

Figure 17 is a detail view of the worm and 75 the worm gear utilized for actuating the compressor.

Figures 18, 19 and 20 are diagrammatic views showing the positions of the compressor units during three equally spaced intervals of one operating cycle of the machine. 80

Heretofore, the compressors used in refrigeration systems have been either of one cylinder or two cylinder type. In the operation of such compressors, there is a period 85 when, upon completion of the compression or discharge stroke of the piston, a portion of the compressed refrigerant remains in the compression chamber and as soon as the piston starts on the return or intake stroke, 90 such refrigerant expands and exerts pressure against said piston, thereby causing said piston to move inwardly a slight distance in advance of its driving mechanism. This slight movement of the piston independently 95 of the driving mechanism is made possible by the play normally existing in the operating connections between the piston and the driving mechanism. Such movement of the piston produces a knock which makes the 100 machine undesirable for use on the same floor with the living apartments. This knock or noise is especially noticeable in machines having a gear drive, such as a worm drive,

wherein the expansion of the refrigerant during the intake stroke of the piston produces back-lash in the gear drive.

In the present invention, the compressor units are so disposed that one or more pistons are always under compression, which opposes and checks the movement of the piston under an intake stroke and maintains the actuating mechanism under a constant load at all times, thereby eliminating knocks and back-lash in the driving mechanism and making the machine practically noiseless. In this manner, a quiet-running machine is provided and the operating stresses to which the actuating mechanism is subjected is evenly distributed through the complete cycle of operation of the machine.

In the type of machine herein disclosed, a worm gear drive is shown and it is especially desirable that the worm gear be maintained in proper engagement with the worm at all times in order to eliminate back-lash.

Referring by numerals to the accompanying drawings, 10 indicates a casing which is preferably of cylindrical shape and is supported on a base 11 provided with a concave pocket 12 for receiving the lower portion of said casing. A series of studs 14 are welded or brazed to casing 10 and extend through suitable apertures formed through the curved wall of base 11 and receive nuts 15 by means of which casing 10 is secured in position on said base. The upper portion of said casing terminates in an upwardly presented extension 16 in which are formed cylindrical chambers 17, 18 and 19, respectively, which are disposed in vertical alignment with the axis of casing 10. Casing 10 is preferably formed open-ended and is closed by end plates 20 which are bolted to said casing and are provided with radial and end-thrust ball bearings 21, in which are arranged the ends of a shaft 22 which extends axially through said casing.

A series of eccentrics 24, 25 and 26 are keyed to shaft 22 in alignment with cylinders 17, 18, and 19, respectively and engage at diametrically opposed points bearing blocks 27 and 28, said points of engagement being in axial alignment with the respective cylinders. These blocks are held against the respective eccentrics by means of tie rods 29 which are arranged in pairs on each side of each eccentric. Pistons 30, 31 and 32 are secured to corresponding blocks 27 and operate in the respective cylinders 17, 18 and 19. One end of shaft 22 is threaded as indicated at 22^a for receiving a nut 34 which bears against the hub of a worm gear 35 and locks the latter in position. Worm gear 35 operates in a chamber 36 which is formed in an extension 10^a of casing 10 and is separated from the interior of said casing 10 by a suitable seal 37, hereinafter more fully described. Meshing with worm gear 35 is a

worm 38 which is carried by a shaft 39, the latter being journaled in a tubular housing 40 carried by extension 10^a. Shaft 39 extends outwardly from said tubular housing and is adapted to be driven in any suitable manner. The inner end of hub of gear 35 is extended as indicated at 35^a and bears against a washer 41 which forms part of the sealing device 37.

Bearing against the opposite end of said washer is one end of a spacing sleeve 42 while the opposite end thereof bears against eccentric 26. Similar sleeves 44 are interposed between the remaining eccentrics and a sleeve 45 is interposed between eccentric 24 and the corresponding bearing 21. The ends of these spacing sleeves are provided with annular V-shaped grooves 46 as shown in Figure 12 and the eccentrics are provided with grooves 47 which are arranged eccentric with the axis of shaft 22 and adapted to cooperate with grooves 46. These grooves are adapted to receive between them metallic rings 48 formed of lead or similar material which rings when hub portion 35^a and the spacing sleeves are drawn against each other and against the respective eccentrics and washer 41, provide a metallic fluid-tight seal which prevents the escape of refrigerant or oil from the interior of casing 10 along the shaft 22 into the worm drive chamber 36. Engaging the ends of washer 41 and held in close sealing contact therewith are washers 49 which are made of special anti-friction material, which may be of metal-alloy or some other composition. These washers are freely arranged on hub extension 35^a and on spacing sleeve 42 and bearing against said washers and maintaining the latter in close contact with washer 41 are washers 50 which are held in position by spaced flexible plates or diaphragm members 51 secured to said washers in any suitable manner. These plates are held against annular shoulder 52 by rings 54.

Shoulders 52 are formed integral with casing 10 and project inwardly therefrom to form the dividing wall between the interior of casing 10 and the worm gear chamber 36. Rings 54 are secured in position in any suitable manner.

A metallic packing 55 is arranged on each side of each diaphragm member 51 and suitable V-shaped grooves formed in shoulders 42 and rings 54 and form a fluid-tight seal to prevent the passage of refrigerant from the interior of casing 10 to chamber 36. Rotatably mounted on the spacing sleeves 42 and 44 are collars 56 which are adapted to be engaged by tie rods 29 and form a guide during the movement of the pistons.

The diaphragm members 51 maintain disks 50 under pressure against disks 49, thereby forming a fluid-tight seal for preventing passage of fluid from the casing chamber

to chamber 36 and are controlled by the pressures in the respective chambers so that as the pressure increases in one of the chambers, the respective diaphragm member 51 is actuated to increase the pressure with which the corresponding disk 50 is applied to one of the disks 49.

When the machine is in operation, the chamber in the casing is under pressure and causes the inner one of diaphragm members 51 to bear against the corresponding disk 50 so that the pressure between the latter and the corresponding anti-friction disk 49 is increased, while if the chamber of the casing is placed under vacuum, due to the expansion of gases in the refrigeration system when the machine is stationary, the pressure in chamber 36 will force the outer one of diaphragm members 51 and the corresponding disk 50 against one of the members 49, thereby insuring a perfect sealing contact between the respective members and preventing passage of fluids between the respective chambers.

The chamber of the casing 10 is partially filled with oil or other suitable lubricant for lubricating the actuating mechanism of the compressor and chamber 37 is partially or wholly filled with oil while chamber 36 is preferably filled with grease. Housing 40, which contains worm 38, is provided with an extension 40^a also provided with a suitable seal so that all danger of the fluid used as refrigerant escaping from the machine is eliminated.

The cylindrical extension 16 is closed at the upper end by a cylinder head 57 which is attached in position by means of bolts or other fastening devices 58 which are seated in the horizontal flange of cylinder head 57 and engage horizontal flange 16^a of casing 16. Cylinder head 57 consists of an outer wall 57^a which is preferably rectangular in plan view and rests on horizontal wall 16^a of casing 16. Formed integral with side walls 57^a and the horizontal or top wall 57^b are partition walls 57^c which extend longitudinally of cylinder head 57 and serve to divide the interior thereof into three chambers, namely, a middle or high pressure chamber 59, a discharge chamber 60, and a return or intake chamber 61. Chambers 59 and 60 are connected together by ports 62 which are formed in one of the partition walls 57^c whereby the compressed refrigerant can pass from chamber 59 to chamber 60. Connections 64 convey the compressed refrigerant under pressure to the condenser coils of the refrigeration system while connections 65 return the expanded refrigerant to intake chamber 61 after said refrigerant has been circulated through the refrigeration system. From the intake chamber 61 the refrigerant is conveyed by the connection 66 to a port 67 of each cylinder 17 from

which the refrigerant is passed through a port 68 formed in the peripheral wall of each piston into the interior thereof during the intake stroke of such piston. These pistons are formed open-ended and are closed by cup valves 69 which are slidably arranged on the upper ends of said pistons and have a lost motion relative thereto so that on the intake stroke of the piston the cup valve thereof is displaced, thereby permitting the refrigerant to pass from the interior of the piston through apertures 70 into the respective cylinder.

On the compression stroke of the piston, valve 69 is seated, thereby closing aperture 70 and trapping the refrigerant in the cylinder and forcing it under pressure into the high pressure chamber 59. A disk valve 71 is slidably mounted in a boss 72 which extends downwardly from the horizontal wall 57^b and is disposed in axial alignment with each cylinder. This valve is adapted to be seated on top of the corresponding cylinder, thereby closing communication between said cylinder and the high pressure chamber 59 during the intake stroke of the piston, thereby preventing escape of refrigerant from high pressure chamber 59 through the cylinders. The faces of walls 57^a and 57^b are provided with V-shaped grooves which when cylinder head 57 is in position on casing 16 coincide with similarly shaped grooves formed in the horizontally disposed wall 16^a and are adapted to receive suitable metal packing 74 which forms a fluid-tight joint and seals the respective chambers.

Chambers 60 and 61 have arranged therein suitable screens 75 disposed at suitable levels and serving as strainers to prevent dirt or other foreign substance from circulating through the system. The upper end of pipe connection 66 extends upwardly through the screen 75 in chamber 61 and terminates a short distance below the top of said chamber. The lower end of intake pipe 65 extends downwardly through screen 75 and terminates a short distance above the bottom of said chamber. In this manner the refrigerant is discharged below screen 75 and has to pass upwardly through said screen before it is returned to the cylinders.

In the operation of the compressor, a certain amount of oil is carried by the refrigerant into the refrigeration system and chambers 60 and 61 serve as separators for collecting the oil and separating it from the refrigerant and returning it to the casing. The oil in the low pressure chamber 61 is returned to the casing by a pipe connection 76, the upper end of which extends into said chamber and the lower end of which extends through casing 10 into the casing chamber. The oil in high pressure chamber 60 is discharged by a pipe 77 which leads from said chamber into the chamber of cas-

ing 10. The upper end of pipe 77 is normally closed by a float valve 78 which is arranged in chamber 60 and normally closes said pipe and is designed to be opened to discharge the oil when the latter reaches a predetermined level in chamber 60. This precaution is necessary in order to prevent the refrigerant from returning to casing 10.

The machine consists of three compression units or cylinders and the eccentrics or actuating members used for operating the pistons are spaced equidistant about the axis of the shaft, in the present instance, sixty degrees apart, so that the load is spaced 15 equally about the axis of the shaft so as to maintain a constant load on the gear drive and prevent back lash when one of the pistons starts on the intake stroke.

Where only one or two pistons are used for compressing refrigerant, the latter, upon the commencement of the intake stroke of the piston, expands in the cylinder and produces back pressure on the piston, which back pressure results in back lash causing 25 noisy operation of the machine. By using three or more compression units, operatively spaced equally about the axis of the driving shaft, the intake stroke of one of the pistons is opposed by two or more compression 30 strokes of the other pistons which overcome the back pressure produced by the piston under intake stroke and maintain a constant load on the shaft so that the back lash and the resultant noisy operation is thereby 35 eliminated.

The disposition of pistons during one cycle of the operation of the machine is progressively illustrated in Figures 18 to 20.

In the operation of the machine, shaft 39 driven in any suitable manner actuates 40 through worm 38 worm gear 35 which, being fastened to shaft 22, operates eccentrics 24, 25 and 26. These eccentrics having engagement with blocks 27 to which are secured 45 the lower ends of pistons 30, 31, and 32, set in operation said pistons which compress the refrigerant in the respective cylinders and force said refrigerant under compression into high pressure chamber 59 by unseating the respective valves 71. Each 50 valve 71 is unseated by the compression stroke of the respective piston and as soon as said piston begins its intake stroke, disk 71 is seated due to the pressure prevailing 55 in chamber 59. From chamber 59 the refrigerant passes through port 62 to the lower portion of discharge chamber 60 and then passes upwardly through screen 75 and is conveyed to the refrigerating system by 60 pipes 64.

Any oil which has been absorbed by the refrigerant in passing through the cylinders is collected in chamber 60 and discharged through pipe 76 back into the casing 10.

65 After the refrigerant has been circulated

through the refrigerating system, it is returned through pipe 65 to the lower portion of chamber 61 and passes upwardly through screen 75 into the upper portion of said chamber from which it is then led through 70 pipe 66 to one of the ports 67 and when the respective piston reaches its downward stroke, the corresponding inlet port 68 of said piston is brought in alignment with port 67 allowing the refrigerant to pass into 75 the interior of said piston from which it then passes through port 70 of the displaced cup valve 69 into the respective cylinder to be compressed and again recirculated through the refrigerating system. 80

I claim:

1. A compressor comprising a casing having a main chamber and three compression chambers leading therefrom, a revoluble shaft journaled in said main chamber, a valved piston operating in each compression chamber, a cylinder head closing the outer ends of said compression chambers and provided with a high pressure chamber communicating with said compression chambers and a low pressure chamber having a connection adapted to communicate with ports arranged in each piston, a gear drive for said shaft, and eccentrics fixed to said shaft and in operative engagement with said pistons, said eccentrics being spaced in predetermined relation about the axis of said shaft for spacing the compression strokes of said pistons equally through each revolution of said shaft whereby said shaft and said gear drive is under a constant load. 90

2. A compressor comprising a main casing, a plurality of compression chambers leading from said main casing, a detachable head for closing the ends of said compression chambers, said head being provided with a high pressure chamber communicating with each of said compression chambers and a high pressure discharge chamber communicating with said high pressure chamber and an intake chamber separate from said high pressure chamber, a valve for controlling the communication between each compression chamber and said high pressure chamber, a piston operating in each compression chamber, actuating means in said main casing for said pistons, a discharge pipe leading from the upper end of said high pressure discharge chamber, an inlet pipe extending into said intake chamber and terminating in the lower portion thereof, connections leading from said intake chamber to each piston, said pistons being provided with inlet ports adapted to register with said connections, and oil discharge pipes leading from said intake and high pressure discharge chambers to said main casing for discharging thereinto the oil collected in said chambers. 115

3. A compressor comprising a main cas- 130

ing provided with a plurality of compression chambers leading therefrom, a detachable head for closing the ends of said compression chambers, said head being provided with an intermediate chamber communicating with each of said compression chambers and a high pressure discharge chamber and an intake chamber, said discharge chamber having communication with said intermediate 5 chamber and said intake chamber having communication with said compression chambers, a check valve for controlling the communication between each compression chamber and said intermediate high pressure 10 chamber, a revoluble shaft journaled in said main casing, a piston operating in each compression chamber, and operating connections between said shaft and each piston, said connections being so disposed that the 15 pressure strokes of the pistons are equally distributed about the axis of said shaft.

4. A compressor comprising in combination a main casing provided with a plurality of compression chambers leading therefrom, a detachable head for closing the ends of said compression chambers, said head being provided with an intermediate chamber communicating with said compression chambers, and a discharge and an intake chamber, 25 said discharge chamber having communication with said intermediate chamber, a connection leading from said intake chamber to each compression chamber, a hollow piston operating in each compression chamber and 30 provided with a port for establishing communication between the interior of said piston and said intake connection, displaceable valve head for each piston for controlling the passage of the compressible fluid from the interior of the piston to the respective 35 compression chamber, check valves arranged in said intermediate chamber for controlling the communication therebetween and the respective compression chambers, a revoluble 40 shaft journaled in said main casing, and means on said shaft for actuating said pistons successively in predetermined relation.

5. A compressor comprising a casing provided with a plurality of compression chambers arranged in a straight line with each other, a detachable cylinder head for closing the ends of said compression chambers and provided with an intermediate high pressure chamber common to all of said compression 50 chambers, and a high pressure discharge chamber and an intake chamber, passageways connecting said intermediate chamber with said discharge chamber, connections connecting said intake chamber with each 55 compression chamber, a check valve for controlling the communication between each compression chamber and said intermediate chamber, a revoluble shaft journaled in said casing, a piston operating in each compression chamber, and means carried by said 60

shaft for actuating said pistons, said means being disposed sixty degrees apart about the axis of said shaft for progressively actuating said pistons.

6. A compressor comprising a casing provided with a plurality of compression chambers leading therefrom, a detachable head for closing the open ends of said compression chambers, said detachable head being provided with an intermediate chamber common to all of said compression chambers and with a high pressure discharge chamber and low pressure intake chamber, a discharge connection leading from the upper portion of said high pressure discharge chamber, an oil discharge connection leading from the lower portion of said high pressure chamber to said casing, a float valve in said high pressure discharge chamber controlling the discharge of oil through said oil discharge connection in accordance with the level of the oil contained therein, inlet connections connecting the intake chamber with the respective compression chambers, said inlet connection terminating in the upper portion of said inlet chamber, an intake connection leading into said intake chamber, said intake connection terminating in the lower portion thereof, an oil discharge connection leading from said intake chamber to said 70 casing, pistons operating in said compression chambers, check valves for controlling the communication between the respective compression chambers and said intermediate chamber, and means for actuating said pistons.

7. A compressor comprising a casing provided with a plurality of compression chambers leading therefrom, a detachable head for closing the open end of said compression chambers, said detachable head being provided with an intermediate chamber common to all of said compression chambers and with a high pressure discharge chamber and low pressure intake chamber, a discharge connection leading from the upper portion of said high pressure discharge chamber, an oil discharge connection leading from the lower portion of said high pressure chamber to said casing, a float valve in said high pressure discharge chamber controlling the discharge of oil through said oil discharge connection in accordance with the level of the oil contained therein, inlet connections connecting the intake chamber with the respective compression chambers, said inlet connection terminating in the upper portion of said inlet chamber, an intake connection leading into said intake chamber, said intake connection terminating in the lower portion thereof, a strainer arranged in said intake chamber and interposed between the respective ends of said intake pipe and said inlet pipe, an oil discharge connection leading from said intake chamber to said casing, pis- 75 80 85 90 95 100 105 110 115 120 125 130

tons operating in said compression chambers, check valves for controlling the communication between the respective compression chambers and said intermediate chamber, and means for actuating said pistons.

8. A compressor comprising a casing provided with a plurality of compression chambers leading therefrom, a detachable head for closing the open end of said compression chambers, said detachable head being provided with an intermediate chamber common to all of said compression chambers and with a high pressure discharge chamber and low pressure intake chamber, a discharge connection leading from the upper portion of said high pressure discharge chamber, a strainer in said high pressure discharge chamber interposed between said high pressure discharge connection and said inlet passage, an oil discharge connection leading from the lower portion of said high pressure chamber to said casing, a float valve in said high pressure discharge chamber controlling the discharge of oil through said oil discharge connection in accordance with the level of the oil contained therein, inlet connections connecting the intake chamber with the respective compression chambers, said inlet connections terminating in the upper portion of said inlet chamber, an intake connection leading into said intake chamber, said intake connection terminating in the lower portion thereof, an oil discharge connection leading from said intake chamber to said casing, pistons operating in said compression chambers, check valves for controlling the communication between the respective compression chambers and said intermediate chamber, and means for actuating said pistons.

9. A compressor comprising a casing provided with a plurality of compression chambers leading therefrom, a detachable head for enclosing the ends of said compression chambers and provided with an intermediate chamber communicating with said compression chambers and provided with a high pressure discharge chamber and a low pressure intake chamber, said discharge chamber having communication with said intermediate chamber and said intake chamber having communication with said compression chambers, a check valve for controlling the communication between each compression chamber and said intermediate high pressure chamber, oil discharge pipes leading from said intake chamber and high pressure discharge chamber to said main casing for discharging thereinto the oil collected in said chambers, a piston operating in each compression chamber, and actuating means in said casing having positive operating connections with said pistons.

10. In a compressor the combination with a main casing provided with a plurality of

compression chambers leading therefrom, and pistons operating in said compression chambers, of a detachable head adapted to be secured to said casing for enclosing the ends of said compression chambers, said head being provided with an intermediate chamber communicating with said compression chambers and a high pressure discharge chamber and a low pressure intake chamber, said discharge chamber having communication with said intermediate chamber, a connection leading from said intake chamber to each compression chamber, and a check valve for controlling the communication between each compression chamber and said intermediate high pressure chamber.

11. In a compressor the combination with a main casing provided with a plurality of compression chambers leading therefrom, and pistons operating in said compression chambers, of a detachable head adapted to be secured to said casing for enclosing the ends of said compression chambers, said head being provided with an intermediate chamber communicating with said compression chambers and a high pressure discharge chamber and a low pressure intake chamber, said discharge chamber having communication with said intermediate chamber, a connection leading from said intake chamber to each compression chamber, a check valve for controlling the communication between each compression chamber and said intermediate high pressure chamber, a discharge pipe leading from the upper end of said high pressure discharge chamber, an inlet pipe extending into said inlet chamber and terminating in the lower portion thereof, and oil discharge pipes leading from said intake chamber and said high pressure discharge chamber to the interior of said main casing for discharging thereinto the oil collected in said chambers.

12. In a compressor the combination with a main casing provided with a plurality of compression chambers leading therefrom, and pistons operating in said compression chambers, of a detachable head adapted to be secured to said casing for enclosing the ends of said compression chambers, said head being provided with an intermediate chamber communicating with said compression chambers and a high pressure discharge chamber and a low pressure intake chamber, said discharge chamber having communication with said intermediate chamber, a connection leading from said intake chamber to each compression chamber, a check valve for controlling the communication between each compression chamber and said intermediate high pressure chamber, a discharge pipe leading from the upper end of said high pressure discharge chamber, an inlet pipe extending into said inlet chamber

and terminating in the lower portion thereof, oil discharge pipes leading from said intake chamber and said high pressure discharge chamber to the interior of said main casing for discharging thereinto the oil collected in said chambers, and valve means in said high pressure discharge chamber for opening and closing the end of the oil discharge pipe leading therefrom.

10 13. In a compressor the combination with a main casing provided with a plurality of compression chambers leading therefrom, and pistons operating in said compression chambers, of a detachable head adapted to be secured to said casing for enclosing the ends of said compression chambers, said head being provided with an intermediate chamber communicating with said compression chambers and a high pressure discharge 15 chamber and a low pressure intake chamber, said discharge chamber having communication with said intermediate chamber, a connection leading from said intake chamber

ber to each compression chamber, a check valve for controlling the communication between each compression chamber and said intermediate high pressure chamber, a discharge pipe leading from the upper end of said high pressure discharge chamber, an inlet pipe extending into said intake chamber 20 and terminating in the lower portion thereof, oil discharge pipes leading from said intake chamber and said high pressure discharge chamber to the interior of said main casing for discharging thereinto the oil collected in said chambers, and a float valve arranged in said high pressure chamber for closing the oil discharge pipe leading therefrom when the oil contained therein falls below a predetermined level and for opening said discharge pipe when the oil in said high pressure chamber rises to a predetermined level. 25 30 35 40

In testimony whereof I hereunto affix my signature this 16th day of June, 1925.

JOHN O. CARREY.
